PRINTING TELEGRAPH RECEIVER

Luther S. Rose, Honolulu, Territory of Hawaii

Application August 29, 1941, Serial No. 408,886

15 Claims. (Cl. 178—26)

The present invention relates to means for receiving messages transmitted in code and the primary object of the invention is to provide a receiving system wherein coded messages received in the form of electrical impulses will be automatically converted into print as upon a typewriter.

A further object of the invention is to provide a printing receiving system embodying means for receiving international Morse code or any code consisting of a combination of dots and dashes, or in other words long and short electrical impulses, employed to represent characters of the alphabet and figures, the said means functioning to analyze or convert the dots and dashes into a typewritten message.

A further object is to provide a device of this character which may be universally used to decode messages, and which device is adaptable for use in wire telegraphy as well as in connection with wireless telegraphy for the translation of code signals into print.

A further object of the invention is to provide a receiving system for code messages wherein the code signals are translated into print by electromagnetic means operable for routing the signals to proper key actuating means of the typewriter.

A further object resides in the provision of means for providing spaces between words in the received messages as well as providing for automatically returning the typewriter carriage at the proper instant without having to receive a transmitted character or characters to effect return of the carriage.

A still further and important object of the invention is to provide a code receiving and printing system of this character wherein the number of control relays is reduced to a minimum, thus providing for simplicity and low manufacturing cost.

A still further object is to provide a receiving system for code messages which may be readily associated with most any standard typewriter for typing the code messages into typewritten messages.

Other objects and advantages of the invention will be apparent from the following detailed description taken in connection with the accompanying drawings forming a part of this specification and in which drawings:

Figure 1 is a wiring diagram showing a preferred form of the receiving apparatus.

Figure 2 is a view showing a preferred form of circuit controlling switch means for the receiving apparatus.

Figures 3, 4 and 5 are diagrammatic views illustrating progressive positions of the electro-mechanical switching means.

In the drawings and wherein like reference characters designate corresponding parts throughout the several views, the numeral 5 may generally designate a typewriter having the usual key levers 6 which operate type bars in the usual well known manner.

10 10 A rectifier 7 is connected to the receiving line 8 over which the electrical impulses from the sending station are received; these electrical impulses or signals being delivered over conductors 9 to a receiving relay 10. The rectifier 7 may be of any preferred type and will allow the relay 10 to operate on either A. C. or D. C. current. The relay 10 is preferably a sensitive relay since it functions to pick up the weak signals and relay the impulses to the local circuit of the apparatus. 15 The local circuit is energized by a battery or any suitable source of electric current 11, having one side grounded as at 12 and its opposite terminal connected thru line 13 with the contact 14 of a circuit breaking or open circuiting switch 15 having a switch arm 16.

The receiving relay 10 has an armature 17 movable between contacts 18 and 19, the armature being connected thru battery line 20 with the switch 15 and being normally held in engagement with the contact 18 by a spring 18'.

The contact 18 forms one terminal of two parallel connected relays 21 and 22, the opposite terminals of which are connected thru a variable resistor 23 to ground 24. The relay 21 may be considered as being a control relay and is slower in action than the receiving relay 10, while the relay 22 is slower in operation than the relay 21 and operates to give an extra space. The armature 25 of relay 21 is connected to battery line 20 thru line 26 and is normally held out of engagement with contact 27 by a spring 27'. The contact 27 is connected with the armature 28 of the relay 22. This armature 28 operates between a pair of fixed contacts 29 and 30 at one side 30 of the armature and a flexible contact 31 at the other side of the armature against which the armature is normally urged as by a spring 31'.

The contacts 28 and 31 are both connected by line 32 to one terminal of an electromagnet or solenoid 33 which is grounded as at 34, while the contact 29 forms one terminal of a carriage return coil or solenoid 35 having its other terminal connected with a spring contact 36. This spring contact is engageable by a contact bar 37 reciprocable with the typewriter carriage and

being grounded as at 38. The electromagnet or solenoid 33 is used to actuate the spacing bar of the typewriter, or when a paper tape is used to be typed on, this solenoid 33 may act to operate the tape advancing means.

The contact 19 forms one terminal of a slow acting relay 40 having its other terminal connected thru a variable resistor 41 to ground 24. This relay 40 operates with the same delayed action or with the same slowness of speed as does the relay 21. The armature 42 of the relay 40 is connected to the battery line 20 thru line 26 and is normally held out of engagement with the contact 43 by a spring 43'.

While the relays 21, 22 and 40 are more sluggish in operation than the relay 10, they are designed to be adjusted so as to operate at any desired speed either thru adjusting the spring tension on their respective armatures or by varying the amount of current passing thru the coils. It will therefore be seen that relay 10 is sensitive and will operate its armature regardless of the length of the electrical impulses or the speed with which the impulses are received, whereas relays 21, 22 and 40 being more sluggish will operate only after a certain period of time has elapsed after relay 10 has been operated and comes back to normal.

An electromechanical switching means such as shown in Figure 2 serves to route the received signals or impulses for operation of the proper keys of the typewriter and embodies a ratchet means 45 operable for controlling the position of two rotating switches 46 and 47. The ratchet means 45 embodies a ratchet wheel 48 fixed upon a shaft 49 suitably journaled in a support 50. This shaft 49 is rotated by means of a small motor (not shown) which is connected to the shaft thru a sliding clutch 51 of any preferred form. The motor may run continuously and is connected to the shaft 49 thru the sliding clutch 51 with just enough pressure as to cause the shaft 49 to turn only when the dogs 52 and 53 are disengaged from the teeth of the ratchet wheel 48. As shown, the ratchet wheel 48 is provided with six equidistantly spaced apart teeth 54 to 59 inclusive.

Rotation of the ratchet wheel 48 is controlled by two relays 60 and 61 which are respectively grounded on one side as at 62 and 63. One side of the relay 61 is connected thru line 64 with the battery line 20, while one side of the relay 60 is connected thru line 65 with the contact 19 of the relay 10. Thus it will be seen that operation of the ratchet means 45 is controlled by the relay 10 and battery 11. It will be noted that current will flow direct from the battery thru relay 61 to ground 63 and thereby keep the relay 61 energized until the circuit is broken in this line, as will later be seen by the open circuiting switch 18. The relay 61 has an intermediate pivoted armature 66 pivoted at 67 and spring urged against a stop by a spring 68. The armature 69 of the relay 60 is pivoted intermediate its ends upon one end of the armature 66 as at 70 and is normally spring urged against a stop by a spring 71. The dogs 52 and 53 are pivoted on the armature 69 at opposite sides of its pivot 70. A stop arm 72 is also pivoted at the pivot point 70 and coats with a stop lug 73 on the ratchet wheel 48 for holding the ratchet wheel at a starting position when both of the dogs 52 and 53 are disengaged from the ratchet teeth.

When the relay 61 is energized, the dog 53 is forced down to be engaged by the ratchet teeth 54, etc., and the stop arm 72 also moves free of the stop lug 73 such as in Figure 3. Now, each time the receiving relay 10 is actuated and causes the armature 17 to momentarily engage contact 19, a circuit will be closed thru relay 60 and cause its armature 69 to move downward as in Figure 4 so that the ratchet wheel 48 is allowed to rotate one notch or step in the direction indicated by the arrow. Thus, when the relay 61 is energized, the ratchet wheel 48 will be turned one notch or step each time an electrical impulse is received thru the relay 60.

The solenoids for operating the keys of the typewriter are arranged in banks and a switching arrangement is provided for completing a circuit thru these banks in sequence. For convenience these key actuating solenoids will be referred to by the letters and numerals with which they are associated. While only five banks of solenoids have been shown, this number may be increased in accordance with the number of code characters to a code group which it is desired to receive. In the arrangement illustrated, the numeral 15 represents a bank of two solenoids or electromagnets for operating the keys T and E; 16 a bank of four solenoids for operating the keys M, N, A and I; 17 a bank of eight solenoids for operating the keys O, G, K, D, W, R, U and S; 18 a bank of sixteen solenoids for operating the keys H, V, F, L, P, J, B, X, C, Y, Z and Q, four of these solenoids being extra and need not be employed unless necessary; and 19 a bank of solenoids for operating the numeral keys of the typewriter. These key actuating solenoids are each independent of one another and are connected to separate spring contact fingers 80 which are mounted on an insulated strip 81 disposed longitudinally of the shaft 49.

The metal shaft 49 is grounded as at 49' and is provided with metallic segments 81, 82, 83, 84 and 85 which are so spaced about the shaft and of such length and so related to the spring contacts 80 as to complete electrical circuits thru their respective banks of solenoids in sequence when the shaft is rotated in the direction indicated by the arrow. As will be seen, the segment 81 completes a circuit thru the solenoid bank 15 to ground 49'; the segment 82 completes a circuit thru the solenoid bank 16 to ground 49', while the segments 83, 84 and 85 likewise complete circuits thru their respective solenoid banks 17, 18 and 19 to ground 49'. Thus, only one bank of solenoids is closed to the ground 49' at any one time, the rotating switch 46 acting as a stepping switch and progressively closing the circuits to the banks of solenoids, starting with the closing of the circuit to the solenoid bank 15.

Respectively associated with the solenoid banks 15 to 19 is a series of solenoid selector or routing switches 86, 87, 88, 89 and 90 which control opening and closing of circuits to selected solenoids of the banks. The switch 86 may be a single pole double throw switch, the switch 87 a double pole double throw switch, the switch 88 a four pole double throw switch, the switch 89 an eight pole double throw switch and the switch 90 an eight pole double throw switch. The switch blades of the switches are connected to control bars 91 and are held in an upward normal position by springs 92. The switch blade of

the switch 86 is connected by wire 32' to the line 32.

These selector switches 86 to 90 are respectively controlled by a series of holding relays 93, 94, 95, 96 and 97 each having an armature 98 connected to the control bar 91 of their respective selector switches. The armatures 98 are electrically connected by line 99 to the line 64 leading to the battery line 20. Each of the relays 93 to 97 is grounded at one side as at 100 and at their other side are respectively connected to contacts 93' to 97' which are engaged by the armatures 98. Thus the relays 93 to 97 when energized act to operate their respective selector switches thru the control bars 91 and against the action of the springs 92. Also, when the armatures 98 are drawn down they will engage the contacts 93' etc. and maintain a holding circuit thru the relay until the battery circuit is opened again.

The rotating selector switch 47 controls circuits to the holding relays 93 to 97 and embodies a rotating switch arm 102 which is fixed on, but insulated from the metal selector switch shaft 49. This rotating arm 102 is connected to a brush arm 103 which is in turn electrically connected by a line 104 to the contact 43 of the relay 40 whereby upon closing of the relay 40 the arm 102 will be connected to the battery line 20. The rotating switch arm 102 coacts with a series of contacts 105 to 109 inclusive which are in turn respectively connected to the holding relays 93 to 97.

Each of the key levers 6 of the typewriter 5 is provided with an armature 6' with each of which one of the key actuating solenoids is associated in a manner such as indicated at 75° in Figure 1. Thus each time a character has been typed the circuit will be broken at the open circuiting switch 15.

When the circuit is broken at the switch 15, the ratchet means 45 and the selector switches 46 and 47 are all returned to a starting position for proper reception of the next code group. While the arrows showing the direction of rotation of the selector switches 46 and 47 would seem to indicate that these switches rotate counter to the ratchet wheel 48, such is not the case since the switches are on the same shaft with the ratchet wheel and are merely shown in this manner for clearness of the wiring diagram.

An example of the cycle of operation of the receiving system for the code letter "F" as used in the International Morse Code will now be given. The code letter "F" consists of two dots a dash and another dot, or as considered in electrical terms an electrical impulse of short duration followed by another impulse of short duration which is followed by an impulse of longer duration and this by another electrical impulse of short duration, this combination of short and long electrical impulses going to make up the code combination for the letter "F".

In Figure 1, the ratchet means 45 is shown in its starting position for reception of a code group, while the selector switches 46 and 47 are shown at a position when the letter "F" will be typed. Upon closing of the switch 15 a battery circuit is completed thru the relay 61 to ground 63, thus energizing this relay so that its armature moves to the position in Figure 3 with the stop arm 72 disengaged from the stop lug 73 and the dog 53 moved down and engaged by the tooth 54 of the friction rotated ratchet wheel 48. Since the switches 46 and 47 are on the same shaft 49 with 75

the ratchet wheel 48, the switch arm 102 of the switch 47 will now engage contact 105, but segment 81 of switch 46 will not have engaged the contacts 80 of the solenoid bank 15. It will be seen that closing of the switch 15 places the receiver in a starting position as shown in Figure 3, and all of the code groups will begin at this point.

Now, upon receipt of the first short impulse 10 of the letter "F" at the receiving line 8, if it be in the form of alternating current it will be rectified by the rectifier 7, and if direct current it will not necessarily be effected by the rectifier and will in turn cause the receiving relay 10 to become energized and operate the armature 17 which will be only momentarily as this electrical impulse is of short duration. When the armature 17 is actuated by the relay 10 it engages the contact 18 and completes two circuits at the same time, one circuit being thru the relay 60 of the ratchet means 45 and causing the armature 69 to be actuated and allowing the ratchet wheel 48 to be moved up one step as in Figure 4. The second circuit completed by the armature 17 would be from battery line 20 thru armature 17, relay 40 and resistor 41 to ground 24, thereby tending to actuate the relay 40, but in view of the fact that relay 40 is designed to operate sluggishly it does not operate instantly but waits momentarily, while the relay 60 of the ratchet means 45 which is designed to operate quickly will be operated. The relay 40 is supposed to operate on dashes or long impulses only and is adjusted to do so by use of the variable resistor 41, and when properly adjusted will not operate on the dots or short impulses.

By referring to Figure 4 it will be seen that upon actuation of the armature 69 that the dog 53 has been released from the ratchet tooth 54, which is the starting point of all code combinations or the beginning point of each letter, and that the dog 52 has engaged the ratchet tooth 55. Also notice that the switch arm 102 of the selector switch 47 is on the segment 105 which is connected to the holding relay 93 which operates the solenoid selector switch 86, but since the relay 40 is slow in operating and will not operate on short impulses, the circuit is not completed thru relay 93 and the switch 86 will remain in its upward or normal position.

The dot or short impulse is followed by a space, causing relay 10 to become de-energized and the armature 17 returned by the spring 18' to make contact with the contact 18. This in turn connects the relays 21 and 22 into the circuit from battery line 20, armature 17, contact 18, parallel connected relays 21 and 22, thru variable resistor 23 to ground 24.

Now then the spaces between characters of a combination, or dots and dashes of a combination, being of short duration and equal to one dot, will not operate either of the relays 21 or 22, as relay 21 is similar in operation to relay 40, and relay 22 in addition to being a slow operating relay, is slower yet than relay 21, therefore relay 21 will always operate before relay 22 opens the circuit at 31.

The circuit is now open to the relay 60 allowing the armature 69 to be pulled upward by the spring 71, thus releasing the dog 52 and allowing the ratchet wheel 48 to move another step forward with the dog 53 now engaging the ratchet tooth 55. As in Figure 5, the segment 81 of the rotating switch 46 is now engaging the spring contact fingers 80 of the solenoids T and E of the bank 75

and grounding them thru shaft 48 to ground 49', but as neither of the relays 21 or 22 have been actuated, neither of the solenoids in the bank 78 will be energized to operate a key of the typewriter.

The second impulse in the combination for the letter "F" is also of short duration and appears immediately following the first dot and space. Now then, when the second impulse is received, the relay 18 is operated which in turn causes the ratchet means 45 to operate, moving the rotating switch arm 102 on the segment 108 of the switch 47 and placing the relay 84 in condition to-be actuated if and when relay 48 is actuated, as the circuit is never complete until armature 42 of relay 48 has closed the circuit at 48, and as the second impulse is of short duration it will not cause the relay 48 to actuate, therefore the circuit is left open thru the relay 84, with the switch 87 in its upward normal position as in Figure 1.

The second impulse is immediately followed by a space and this space followed by a third impulse which is of longer duration. This will actuate the ratchet means 45 and will cause the slow acting relay 48 to actuate its armature 42 causing the relay 85 to be operated thru the circuit: battery 11, switch 15, 20, 26, armature 42, 43, 104, 103, rotating switch arm 102, segment 107 and thru relay 85 to ground. The relay 85 being energized attracts its armature 98 and causes a connection to be made at the contact 85' and at the same time operates the switch arms of the switch 88 in a downward position as in Figure 1. It may here be well to mention that the solenoid selector switches 86 to 90 remain in an upward or normal position for the short impulses or dots and are moved downward by their respective relays 83 to 87 on the long impulses or dashes of the code combination.

We now have another circuit which is completed from battery 11, switch 15, 20, 64, 89, armature 98 of relay 85, 95' and thru relay 85 to ground, thereby completing this circuit and keeping the relay 85 energized even after the moving contact 102 has moved to another segment of the switch 47. This circuit will therefore remain closed until the circuit is opened at the switch 15 or anywhere in series with the circuit to the battery 11.

Now then, as the third or long impulse is followed by a space of short duration the armature 11 of relay 18 is returned to the position as shown engaging contact 18; also the shaft 48 of the switch 48 has now been rotated to a position where the segment 83 makes contact with the contact fingers 89 of the solenoid bank 77 and connects the solenoids 77 to ground at 49'. In view of the fact that the space following the third electrical impulse is of short duration it will not cause the relay 21 to be actuated, neither the relay 22, therefore we will not have a complete circuit thru the solenoid bank 77 into ground 49' and none of these solenoids in this bank will be caused to operate.

The fourth and last impulse of the code combination for the letter "F" follows a space of short duration and causes the ratchet means 45 to be actuated, which in turn moves the contact arm 102 of the switch 47 to the segment 108 and the segment 84 of the switch shaft 48 into engagement with the spring contacts 88 of the solenoid bank 78 as in Figure 1. This position of the contact arm 102 and the segment 84 is at the end of the last impulse and after the receiv-

ing relay 18 is de-energized. As mentioned, the contact arm 102 of switch 47 is now making contact with the segment 108 leading to relay 86, but this relay 86 cannot be caused to actuate until the circuit is closed by the slow acting relay 48, therefore the relay 86 will not operate the selector switch 88 on the fourth impulse as it is of short duration and the armature 11 of relay 18 has now been returned, breaking connection at the contact 18. The armature 11 when returned to the position shown making connection with the contact 18 completes the circuit to relays 21 and 22 which are sluggish in operation, this circuit being battery 11, 13, 15, 20, armature 17, contact 18, relay 21, variable resistor 23, and to ground 24. A circuit thru the solenoid bank 78 is now only open at the point between the armature 25 of the relay 21 and the contact 27.

Now then, as the amount of time elapsed after the fourth and last impulse is greater than the spacing time between any of the electrical impulses for that combination, (this spacing time being equal to one dash) the relay 21 will be energized for a period of time sufficient to draw its armature 25 into engagement with the contact 27, but as relay 22, which is connected in the same circuit is slower yet in operation than the relay 21, this relay 22 will not have had time to actuate, even after relay 21 has actuated. At this point a circuit will be completed from 27 thru armature 28, contact 31, 32, and down thru solenoid 33 to ground 34. This solenoid 33 employed to cause the typewriter to make spaces, therefore spaces are made on the typewriter regardless of whether a letter has been typed or not each time the relay 21 or 22 is actuated.

Upon actuation of the solenoid 33 we have another circuit beginning at line 32' and completing the circuit thru one of the key actuating solenoids, causing only one letter and one only to be typed on the typewriter. This circuit is completed thru a of switch 86, b, c, and as segment 81 is not active the circuit is not completed thru solenoid bank 78 and continues on thru switch 87 to d, e, and as segment 82 is not active the solenoid bank 78 will not be actuated and the circuit continues on from e to f, up thru g to h, solenoid k, and as the segment 84 is now connecting the bank of solenoids 78 thru the shaft 48 to ground 49', the solenoid k will actuate the typewriter key for the letter "F," causing this letter alone to be typed.

The open circuiting switch 15 is adapted to open momentarily each time a key of the typewriter has been operated and while shown in Figure 1 for convenience only as being operated by the armature of the solenoid 15, this switch is intended to be associated with the spacing bar mechanism of the typewriter whereby the switch 15 will be opened each time that a letter or character is typed or a space made. As will be seen, when the switch 15 is opened all circuits of the receiver will be open circuited. This causes several things to happen. First the relays 83 to 87 will have been cleared and their switch actuating armatures returned by the springs 92 to normal position. The next thing that happens is the ratchet means 45 is caused to rotate in the direction of the arrow to a normal position as in Figure 1 so that it may be ready to start at the beginning again for another letter. Opening of the switch 15 opens the circuit to the relay 81 whereby its armature 86 is pulled down by the spring 88. The armature 86 being pivoted

at 67 withdraws the dogs 52 and 53 from engagement by the teeth of the ratchet wheel 48 so that the wheel is free to turn and moving with it the shaft 49 whereby the switches 46 and 47 are returned to a normal or starting position. The stop lug 73 when it engages the stop arm 72 causes the ratchet wheel 48 to be stopped at the position shown in Figure 1. As the switch 15 is only opened momentarily, until the typewriter key has been returned to normal, the relay 61 is again energized and attracts its armature 66, whereby the stop arm 72 releases the stop lug 73 and the dog 52 moves down and is engaged by the tooth 54 of the ratchet wheel as in Figure 3. With reference to Figure 3, all of the code groups begin at this point with the switch arm 102 of the switch 47 always on segment 105 during the first impulse as in Figure 4, and the segment 81 of the switch 46 always engaging the contacts 80 of the solenoid bank 75 at the end of the first impulse as in Figure 5.

If the code combination for a certain letter consists of three impulses the segment 83 of the switch 46 will always engage the contact fingers 80 of the third solenoid bank 77 at the end of the combination. If the letter consists of a combination of four electrical impulses the segment 84 will make connection with the fourth solenoid bank 78 at the end of the code combination, and so on for any code letter group, while the contact arm 102 of the switch 47 always makes connection with the segment for the proper relay 83 etc., depending upon the impulse received so that the relay will be actuated in case the relay 40 operates.

After the letter "F," or any other letter has been typed and the switches all returned to normal and the circuits closed again, the armature 17 of relay 10 engages contact 18 and connects relays 21 and 22 into the circuit thru resistor 23 to ground 24, and if no electrical impulses immediately follow the first code group the relay 21 will be caused to operate and as no circuit is completed thru any of the solenoid banks but is completed thru the spacing coil 33 to ground 34, when the relay 21 is actuated no letter will be typed but a space will be made as between two words in a sentence. Now then if still no further electrical impulses are received at 8, the relay 22 will have had time to operate and will in turn cause its armature 28 to be drawn away from the flexible contact 31 into engagement with contact 30 thus momentarily making and breaking the circuit to the spacing coil solenoid 33 and causes another space to occur, the same as between the end of one and the beginning of a new sentence. From this it will therefore be seen that letters will be spaced, words will also have the correct spacing between them, and also the correct spaces will occur between sentences as in any ordinary typed letter.

With reference now to the carriage actuating cell or solenoid 35, contacts 36 and 37, this means acts to cause the carriage of the typewriter to be automatically returned without breaking up words at the end of a typed line. The contacts 36 and 37 form a carriage return switch, the spring contact 36 being fixed and the contact bar 37 being attached to the carriage of the typewriter so as to move back and forth with the carriage. As described before, after a certain length of time the relay 22 is caused to operate and thereby cause the armature 28 to make contact with contacts 29 and 30. During typing of a line nothing ordinarily occurs upon contact of the 75

armature 28 with the contacts 29 and 30 except spacing, but the instant the grounded contact bar 37 moves to a point where it engages contact 36, and thereby closing the circuit thru solenoid 35 to ground 38, the solenoid 35 is energized and actuates a key which in turn will cause the carriage of the typewriter to be returned so that a new paragraph or line may be started.

As will be seen, the key actuating solenoids in each bank 76 to 79 are separate and are only connected together by their respective segments 81 to 85 when one solenoid is to be actuated in that particular bank.

Various switching arrangements other than that shown by the rotary switches 46 and 47 may be employed, such as by a stepping switch arrangement as employed in automatic telephone systems.

Changes in detail may be made to the form of the invention herein shown and described without departing from the spirit of the invention or the scope of the following claims.

I claim.

1. In a printing telegraph receiver, a receiving relay responsive to code signal impulses of long and short duration, a normally closed local circuit, electromechanical switching means for the local circuit, means for controlling the electromechanical switching means thru response of the receiving relay to code signal impulses, and a key actuated open circuiting switch for opening the local circuit and permitting said switching means to be restored to a starting position upon completion of each group of code characters.

2. In a printing telegraph receiver, a receiving relay responsive to code signal impulses of long and short duration, a normally closed local circuit, means responsive to actuation of the receiving relay for typing the characters which are represented by the code signals received, and a key actuated open circuiting switch for the local circuit for restoration of the receiver to a starting condition upon completion of each group of code characters.

3. In a printing telegraph receiver, a receiving relay responsive to code signal impulses of long and short duration, a local circuit, normally open printing circuits, a pair of relays alternately connecting the printing circuits into the local circuit, and selector switching means in each printing circuit and controlled by the receiving relay.

4. In a printing telegraph receiver, a receiving relay responsive to code signal impulses of long and short duration, a local circuit, a dash relay in the local circuit responsive only to impulses of long duration, a space relay in the local circuit responsive only to intervals of equal duration as that of the long impulses, a switch controlled by the receiving relay for alternately energizing the dash and the space relays, and selector printing circuits controlled by the dash and space relays.

5. In a printing receiving apparatus, a receiving circuit including a receiving relay responsive to code signal impulses, a local circuit separate from the receiving circuit, a normally open slow acting dash relay, and a normally energized slow acting space relay in the local circuit and alternately controlled by the receiving relay, a printing circuit controlled by the space relay and including selector switch means, and circuit selector means controlled by the dash relay for operation of the selector switch means.

6. In a printing code receiver, a receiving re-

lay responsive to code signal impulses, a local circuit including a normally open printing circuit and a normally open selector circuit, a slow acting relay for closing the printing circuit, a slow acting relay for closing the selector circuit, a switch controlled by the receiving relay for alternately energizing the slow acting relays, a spacing solenoid energized by actuation of the slow acting relay in the printing circuit, and means for energizing the spacing solenoid a second time after the printing circuit has been closed for a given interval of time.

7. In a printing code receiver, a receiving relay responsive to code signal impulses, a local circuit, a slow acting dash relay and a slow acting space relay in the local circuit and alternately energized by the receiving relay, a second slower acting space relay in circuit with the first mentioned space relay, a spacing solenoid energized by actuation of said first space relay, a switch controlled by said second space relay for energizing the spacing solenoid a second time, and printing circuits controlled by the slow acting relays.

8. In a printing code receiver, a receiving relay responsive to code signal impulses, a local circuit, a slow acting dash relay and a slow acting space relay in the local circuit and alternately energized by the receiving relay, a second slower acting space relay in circuit with the first mentioned space relay, a spacing solenoid energized by actuation of said first space relay, a switch controlled by said second space relay for energizing the spacing solenoid a second time, a carriage return coil, and a second switch controlled by said second space relay for energizing the carriage return coil.

9. In a printing telegraph receiver, a receiving relay responsive to code signal impulses, local circuits controlled by the receiving relay including slow acting signal routing relays, selector switch means for the routed signals, actuating means for the selector switch means and controlled by the receiving relay, a spacing bar solenoid controlled by certain of the slow acting relays, a carriage return coil in the local circuit, and a key actuated open circuiting switch means for the local circuit momentarily operable for opening the local circuit upon printing of a character.

10. In a printing code receiver, a receiving relay responsive to code signal impulses, a local circuit, a normally open slow acting dash relay in the local circuit, a normally energized slow acting space relay in the local circuit, a switch controlled by the receiving relay for opening the space relay and energizing the dash relay each time the receiving relay is energized by a signal impulse, selector switch means for routing the received impulses, and means for progressively actuating the selector switch means each time the receiving relay is actuated.

11. In a printing code receiver, a receiving relay responsive to code signal impulses, a local

circuit, a normally open slow acting dash relay in the local circuit, a normally energized slow acting space relay in the local circuit, a switch controlled by the receiving relay for opening the space relay and energizing the dash relay each time the receiving relay is energized by a signal impulse, selector switch means for routing the received impulses, and means for progressively actuating the selector switch means each time the receiving relay is actuated, including a normally torsioned ratchet wheel, a pair of dogs alternately coacting with the ratchet wheel to permit stepped rotation of the wheel, a constantly energized relay normally urging one of the dogs into holding engagement with the ratchet wheel, and a second relay energized upon actuation of the receiving relay for releasing the first dog and engaging the other dog with the ratchet wheel.

12. In a printing code receiver, a receiving relay responsive to code signal impulses, a local energized circuit controlled by the receiving relay, banks of key actuating solenoids in the local circuit, slow acting space relays in circuit with said solenoids, switch segments progressively connecting the solenoids of each bank in the circuit, selector switch means for the solenoids, and a slow acting dash relay controlling the local circuit to the selector switch means.

13. In a printing code receiver, a receiving relay responsive to code signal impulses, a local energized circuit controlled by the receiving relay, banks of key actuating solenoids in the local circuit, slow acting space relays in circuit with said solenoids, switch segments progressively connecting the solenoids of each bank in the circuit, solenoid selector switch means for each bank of solenoids, a holding relay for each of said switch means, a selector switch for the holding relays, and a slow acting dash relay controlling the circuit to the selector switch.

14. In a printing code receiver, a receiving relay responsive to code signal impulses, a local circuit controlled by the receiving relay, banks of independent key actuating solenoids in the local circuit, switch segments for progressively connecting each bank of solenoids in the local circuit, selector switches for the solenoids of each bank of solenoids, and actuating means for the switches responsive to impulses of long duration.

15. In a printing code receiver a local energized circuit controlled by code signal impulses, two normally energized parallel connected retarded space relays one being operable upon intervals of time between code groups of impulses and the other of said relays being slower in action than the first and operable upon intervals of time between words, a retarded dash relay operable upon impulses of long duration, impulse controlled means alternately connecting the space relays and the dash relay in circuit, and a printing circuit controlled by said relays.

LUTHER S. ROSE.
